UNITED STATES PATENT OFFICE.

THOMAS W. GARNETT AND FRED EMANUEL TORGLER, OF TOPEKA, KANSAS.

ICE-CAN.

1,348,354.

Specification of Letters Patent.

Patented Aug. 3, 1920.

Application filed July 29, 1919. Serial No. 314,083.

To all whom it may concern:

Be it known that we, THOMAS W. GARNETT and FRED EMANUEL TORGLER, both citizens of the United States, residing at Topeka, in the county of Shawnee and State of Kansas, have invented certain new and useful Improvements in Ice-Cans, of which the following is a specification.

The present invention relates to ice molds 10 or containers adapted to receive water to be frozen.

It is well known to those familiar with the art that receptacles or containers of this character are subjected to considerable internal pressure during the expansion of the water as it is converted into ice; in the lifting and dumping of the molded block of ice in the receptacle; and in the general handling, packing and arrangement of the receptacles in the main freezing tank.

It has also been found with the use of prior devices of this character that when the pans or receptacles are overturned to release the block of ice they are impacted with considerable force under the thrust of the block of ice, which weighs between one hundred and four hundred pounds, in such a manner that the seams of the receptacle are burst and opened during such operation. Another 25 disadvantage found with prior receptacles or molds of this character is that the corners are not capable of withstanding the internal pressure and frequently crack or burst. Repair of such injuries to the can 30 can not be permanently or easily made and the cans are practically worthless when so split. A further disadvantage found in prior molds is that the bottoms, under the heavy strain and the expansion incident to 35 the freezing of the water, causes the bottoms to bulge downward within the base flange and form ice blocks with rounded bottoms making the blocks difficult to handle as they will not stand upright, particularly 40 when deposited in delivery wagons and the like.

The object of the present invention is to provide in a simply constructed sheet metal mold or receptacle a construction which obviates all of the above disadvantages and which has additionally the advantage of quickly freeing the block of ice when the can is overturned and of reducing the frictional contact between the sides of the block

and the can during the withdrawal of the 55 block of ice.

Another object of the invention is to provide a construction of mold which may be knocked down and conveniently shipped from the factory to ice plants and the like, 60 and which may be stored in quantities in a relatively small space, the object also embracing a novel joint between the meeting edges of the sheet metal body of the can and the bottom edge of the body and the bot- 65 tom.

With these and other objects in view, the invention consists in certain novel combinations and arrangements of the parts as will more fully appear as the description proceeds, the novel features thereof being 70 pointed out in the appended claims.

For a full understanding of the invention, reference is to be had to the following description and accompanying drawings, in 75 which:—

Figure 1 is a side elevation of a receptacle or mold for ice constructed according to the present invention.

Fig. 2 is a top plan view of the same. 80

Fig. 3 is a fragmentary vertical section through the lower portion of the mold.

Fig. 4 is a bottom plan of the mold.

Fig. 5 is a fragmentary sectional view through the bottom portion of the mold 85 taken between the longitudinal sides thereof.

Fig. 6 is a detail sectional view through one of the longitudinal sides of the mold, showing the body seam of the same.

Corresponding and like parts are referred to in the following description and indicated in all the views of the drawings by the same reference characters.

Referring to the drawing, 10 designates the body of the mold or receptacle which is made of sheet metal and which in cross section is formed substantially rectangular with rounded corners 11. The body 10 tapers from its upper or open end to its lower or closed end to provide a receptacle with a 95 flaring open end adapted to admit the easy withdrawal of a block of ice therefrom. The degree of taper may be varied as but a slight taper is sufficient for the purpose of freeing the sides of the block of ice uniformly and from end to end from the side walls of the mold when the block is being extracted. The body 10 has its rounded cor- 100 105

ners 11 made on preferably two bevel or angular faces 12 which form a gradual curvature at the corners and which are capable of taking up expansion of the block of 5 ice while in the mold and thus prevent the bursting or splitting of the metallic body 10 at the corners.

The body 10 may be made in one or more sections, two being shown in the present instance, and which are so constructed that 10 when assembled the sections or sheets of the body meet and overlap at the longitudinal sides of the body so that the narrow sides of the body are uninterrupted and continuous; thus eliminating the formation of 15 seams at such narrow sides where impact and pressure are constantly exerted during handling of the molds and the dumping of the same. As shown in Fig. 6, the seams in 20 the body 10 are each formed of the overlapping ends of the adjacent sheets of metal and which have interposed between them a strip or layer 13 of tar paper, or other suitable substance forming a packing for effectively and positively sealing the joint 25 between the overlapping ends and for rendering the seam air and moisture tight.

In the present instance the seam is held together by a longitudinal row of bolts 14 30 carrying detachable nuts 15 at the outer sides of the body 10, the bolts being arranged in staggered relation throughout the end of the can and being detachable so that the sections of the can may be separated 35 and the can thus conveniently handled in relatively small space. By virtue of the tapering formation of the body of the can, the sections thereof may be made to telescope or interfit when the sections are 40 separated one from the other, and thus a large number of cans may be knocked down and packed into the same space which is ordinarily required for the storage of one can.

45 Each section of the can is thus substantially U-shaped and the seams of the assembled can are located in the longitudinal sides of the can so that the seams are protected from impact and do not have to sustain the weight of the molded block as the can is overturned or dumped.

The upper edge of the can may be reinforced by a ring 16 which may be of any suitable construction and detachably 50 secured to the upper edge portion of the body 10 by bolts 17 which may be readily removed for knocking the structure down. The lower end of the can is closed by a bottom 18 formed of sheet metal which has its 55 marginal edge portion bent downward and rounded upwardly to form a U-shaped channel flange 19 at the margin of the bottom 18 with the flange opening upwardly to receive therein the lower edge of the 60 body 10. The flange 19 is relatively strong 65

as it comprises a pair of spaced walls capable of withstanding considerable impact and weight and which braces the bottom portion of the can body 10. Detachable bolts 20 may be used in securing the bottom 70 of the can or mold 10 to the lower edge of the sheet metal body for facilitating the knocking down of the mold. In order to seal the bottom of the body 10, a U-shaped packing strip 21 of tar paper, or other suitable yielding insulating material may be employed. As shown in Figs. 3 and 5, the packing strip 21 is of U-shape and fitted in the flange 19 about the lower edge of the body 10 and adapted to receive the bolts 20 75 therethrough for maintaining the packing in position and sealing the packing in the flange 19. The bottom 18 is reinforced against bulging downwardly by the provision of ribs or crimps 22 which are 80 formed diagonally across the bottom and intersect at the intermediate portion thereof. The crimps 22 project upwardly into the can so as to provide a substantial brace with the arch of the brace upward 85 against the mass to be supported, the arch being formed by the upstruck U-shape of the ribs.

A can constructed according to this invention is of substantially normal size and 90 may be handled in the main tank in the usual manner. When the can is dumped over on one of its narrow sides the impact of the weight of the can with the molded block therein is not thrust directly 95 upon the seam of the body, and thus the seam is protected against this impact which usually opens the seam and destroys the can. Furthermore, the arrangement of the seam intermediate the longitudinal sides of 100 the can strengthens said sides and forms a reinforcement for the can to resist internal pressure and also buckling when dumped and otherwise handled. The bottom 18 of the can can not bulge downward as the ribs 105 22 support the weight of the block and prevent the internal pressure during freezing from bending or arching the bottom 18.

110 It is readily appreciated that the various bolts may be withdrawn and the sections of the can separated, and that the sections may be telescoped one into the other and the whole mold or can be packed into relatively small space and nested into other similarly formed molds.

115 Having thus described the invention, what we claim as new and desire to secure by Letters Patent, is:—

1. A knock down ice mold comprising a 120 rectangular body portion, which is divided longitudinally into two complementary U-shaped sections, adapted to be nested in each other, means for detachably connecting the meeting edges of the sections to form a hollow body for the mold, a bottom 125 130

plate having marginal portions constructed to receive and interlock with the edges of the body, and means for detachably securing the bottom plate to the body of the 5 mold.

2. A knock down ice mold comprising a rectangular body portion which is divided longitudinally into two complemental U shaped sections adapted to be nested in 10 each other, the meeting edges of the sections overlapping each other when the sections are operatively assembled, fastening members detachably connecting the overlapping edges of the sections, a bottom 15 plate formed with a marginal channel flange receiving the lower edges of the body sections, and means for detachably securing the bottom plate to the body sections.

3. A knock down ice mold comprising a rectangular body portion which is divided 20 longitudinally into two complemental U shaped sections adapted to be nested within each other, the meeting edges of the sections overlapping when the sections are operatively assembled, bolts detachably connecting the said overlapping edges, a reinforcing band applied to the upper end of the sections, a bottom plate formed with a marginal channel flange receiving the lower 25 edges of the body sections, and fastening members detachably securing the bottom 30 plate and top band in position.

In testimony whereof we affix our signatures.

THOMAS W. GARNETT.

FRED EMANUEL TORGLER.
